AUTOMATIC STARTING MECHANISM

Application filed April 23, 1931. Serial No. 533,278.

This invention relates to automatic starting mechanism and more particularly to a device for protecting the starting mechanism and conserving the source of electrical energy in case the engine fails to start after the starting motor circuit has been energized for a predetermined length of time.

It is an object of the present invention to provide an automatic starting mechanism embodying a novel means for causing the starting circuit to be opened after the same has been energized for a predetermined length of time.

Another object is to provide such a device in which the automatic opening of the starting circuit is secured by means of a heat-responsive device having a heating element which is energized concomitantly with the energization of the starting circuit.

20 A further object is to provide such a device which involves no additional switches or brakes in the circuits nor the use of special auxiliary controlling circuits.

Another object is to furnish such a device 25 which will produce an audible indication to the operator of the failure of the engine to start and remind him to disconnect the automatic starting mechanism before taking steps to remedy the inoperative condition of the 30 engine.

Further objects and advantages will be apparent to those skilled in this art from the following description taken in connection with the accompanying drawing in which the 35 figure is a semi-diagrammatic illustration of a preferred embodiment of the invention, the automatic starting switch elements being shown in elevation and partly in vertical section.

40 In the drawing there is illustrated a starting motor circuit, including a battery 10, one terminal of which is grounded at 11 and the other terminal of which is connected by a lead 12 to an automatic starting mechanism comprising a starting switch having a stationary 45 element 13 connected to the lead 12, a second stationary element 14 and a movable insulated bridging element 16. The stationary element 14 is connected through a lead 17 to a single 50 turn coil 18 which in turn is connected by a

lead 19 to a starting motor SM which is grounded at 21 in order to complete the starting circuit.

The movable element 16 of the starter switch is mounted by suitable insulating 55 means on a magnetic plunger 23 which is normally maintained in its upper position by means such as a spring 24 but which may be drawn down to close the starting switch by a solenoid 26. Said solenoid is included in a 60 control circuit comprising the battery 10, lead 12, ammeter A, manual switch 27 (which may as indicated be the ignition switch of the internal combustion engine) lead 28, solenoid 26, lead 29, fixed contact 31, movable 65 contact 32, spring strip 33 and ground connection 34. The spring strip 33 is arranged to normally hold the contact 32 against the fixed contact 31 whereby closure of the manual switch 27 by the operator will cause 70 energization of the control circuit to close the starting switch.

Means are provided for automatically opening the control circuit when the engine starts, for holding said circuit open as long 75 as the engine is self-operative and for delaying the closing thereof until a predetermined time after the engine has come substantially to rest. As illustrated, these means include a wedge-shaped weight member 36 mounted on 80 the end of the spring strip 33 in the path of movement of a roller 37. Said roller is mounted on the end of a lever 38, pivoted at 39 and having a pin 41 at an intermediate 85 point thereof projecting laterally between a pair of flanges 42 and 43, on a movable magnetic relay plunger 44. A voltage coil 46 and a generator coil 47 are arranged to surround the lower part of the relay plunger 44 and when energized attract the same downwardly. The voltage coil 46 is connected at one end by a lead 48 to the stationary starting switch member 14, and is grounded at its other end at 49. Generator coil 47 is connected at one end by lead 51 to a generator G 95 and is also grounded at its other end at 49. Relay plunger 44 is normally retained in its upper position against a spacing sleeve 52 by means such as a spring 53 whereby the lever 38 is maintained as illustrated out of contact 100

with the weight member 36 so that the contact 32 normally rests against contact 31.

The lead 19 to the starting motor SM is provided with a contact member 54 which is mounted upon the free end of a heat-responsive member 56, suitably insulated therefrom as indicated, the opposite end of said heat-responsive member being fixedly mounted in a suitable manner as indicated at 57. A heating element 58 is arranged to surround the heat-responsive member 56. This heating element is connected at one end to the motor lead 19 as indicated at 59 and is grounded at the other end as at 61.

15 A fixed contact member 62 is mounted in any suitable manner adjacent the movable contact member 54 and is connected by a lead 63 to the lead 17 from the starting motor switch, the arrangement being such that when 20 the heat-responsive member 56 is heated sufficiently to bring contact 54 into engagement with contact 62, the single turn coil 18 is shorted by the connection through said contacts and the lead 63.

25 In the normal operation of the device, closure of the ignition switch 27 closes the control circuit, thus causing the solenoid 26 to close the starting switch 13, 16, 14, completing the starting circuit through the single 30 turn coil 18 and lead 19 to the starting motor SM whereby the starting motor is caused to crank the engine. During this time, the voltage coil 46 is energized by reason of its connection to the starting switch member 14, but 35 the heavy current traversing the single turn coil 18 holds the plunger 44 in its upper position. This holding effect is preferably controlled by means such as an adjustable magnetizable pole piece 64 within the spacing member 52.

If the engine becomes self-operative after a reasonable amount of cranking, the load on the starting motor is thereupon relieved and the consequent reduction of the current 45 through the single turn coil 18 together with the increase of voltage drop through the voltage coil 46 enables the latter to overcome the effect of the single turn coil 18 and the spring 53 and draw the plunger 44 downwardly 50 causing the lever 38 to carry the roller 37 into engagement with the weight member 36 and bend the spring strip 33 backward sufficiently to move the contact 32 away from contact 31. The consequent opening of the control circuit 55 causes the deenergization of the solenoid 26 thus releasing the starting switch plunger 23 whereby the spring 24 operates to open the starting switch. The relay plunger 44 is not immediately released, however, since 60 the voltage coil 46 is traversed by a slight amount of current generated by the starting motor spinning by momentum in its residual field, this current being sufficient to hold the plunger 44 against its pole piece 66 until the 65 starting motor has come substantially to rest.

Before the voltage coil 46 becomes entirely deenergized, the generator G which is driven from the engine, builds up sufficient voltage to energize the generator coil 47 and retain the relay plunger 44 in its lower position, thus holding the contact 32 out of engagement with the contact 31 as long as the engine is self-operative.

If the engine should stall for any reason, the generator coil 47 becomes deenergized and the spring 53 raises the relay plunger 44, releasing the weight member 36 which vibrates for a predetermined length of time due to its pendulous mounting on the spring strip 33 thus giving the engine time to come completely to rest before the contact 32 makes effective engagement with the contact 31. When the vibration ceases and the contact 32 comes to rest against the contact 31, the starting operation is repeated.

During this cranking operation, the heating element 58 is energized by reason of its connection to the motor lead 19, and imparts its heat to the heat-responsive member 56 causing it to be deflected in a direction to move contact 54 into engagement with contact 62.

When the engine becomes self-operative within a normal length of time, the heat-responsive member 56 does not become sufficiently heated to close the contacts 54, 62, and the starting operation takes place as above described. If however, the engine should fail to start owing to improper functional conditions or to a jamming of the starting gearing, the heat-responsive member 56 will after a predetermined time cause contact 54 to engage contact 62 thereby shorting and de-energizing the single turn coil 18. Voltage coil 46 is thereupon allowed to attract the plunger 44 downward, causing the contact 32 to be moved out of engagement with contact 31, breaking the control circuit and releasing the starting switch. As soon as the starting switch opens, however, the voltage coil 46 is deenergized and the spring 53 then returns the relay plunger 44 to its upper position, causing the starting switch to be closed again as soon as the vibrator contact 32 comes to rest against contact 31. The starting switch plunger 23 and relay plunger 44 are thus caused to continuously reciprocate at short time intervals determined by the vibrator time delay element 33. This produces a characteristic clicking sound which warns the operator of the failure of the engine to start and reminds him to open the ignition switch preparatory to taking steps to secure proper starting action.

During this time, the heating element 58 has begun to cool down, since it is connected to the battery only intermittently for short intervals, and when the ignition switch is opened by the operator, the heating element will of course be deenergized. When the in-

operative condition of the engine has been remedied it is thus only necessary for the operator to close the ignition switch 27 whereupon the automatic starting mechanism will

5 be caused to operate in the usual manner.

Although but one embodiment of the invention has been shown and described in detail, other embodiments will become apparent to those skilled in this art and it will 10 be understood that various changes may be made in the proportions and arrangements of the parts here shown without departing from the spirit of the invention as defined in the claims appended hereto.

15 What is claimed is:

1. In an automatic starting mechanism for internal combustion engines, a starting circuit including a source of energy, a starting motor and a starting switch for controlling 20 said motor, opposed electro-magnetic elements adapted respectively to cause the switch to be held closed as long as the engine is being cranked, and to be opened when the engine starts, and means for shorting said 25 electro-magnetic holding element after the starting motor has been energized a predetermined length of time.

2. In an automatic starting mechanism for internal combustion engines, a starting circuit including a source of energy, a starting motor and a starting switch for controlling 30 said motor, means energized by current traversing the starting circuit for causing said switch to be held closed until the engine 35 starts and means for rendering said holding means inoperative after the starting motor has been energized for a predetermined time.

3. In an automatic starting mechanism for internal combustion engines, a starting circuit including a source of energy, a starting motor and a starting switch for controlling 40 said motor, means including an electro-magnetic element energized by current traversing the starting circuit for causing said switch to be held closed until the engine starts, said 45 electro-magnetic element being weakened by the reduction in starting current when the engine starts so as to allow the starting switch to be opened, and thermostatic means for causing said electro-magnetic element to 50 allow the switch to be opened after the starting motor has been energized for a predetermined time.

4. In an automatic starting mechanism for internal combustion engines, a starting circuit including a source of electrical energy, a starting motor and a starting switch for controlling 55 said motor, means for actuating said starting switch including an electro-magnetic element and a control circuit therefor including the source of electrical energy and a control switch, means energized concomitantly with the starting circuit tending 60 to open said control switch, means energized simultaneously therewith for holding said

control switch closed, and means for rendering said holding means inoperative after the starting circuit has been energized a predetermined length of time.

5. In an automatic starting mechanism for 70 internal combustion engines, a starting circuit including a source of electrical energy, a starting motor and a starting switch for controlling said motor, means for actuating said starting switch including an electro-magnetic element and a control circuit therefor including the source of electrical energy and a control switch, electro-magnetic means energized concomitantly with the starting circuit tending to open said control circuit, 75 electro-magnetic means energized simultaneously therewith for holding said control switch closed, and means for shorting said electro-magnetic holding means after the starting circuit has been energized a predetermined length of time.

6. In an automatic starting mechanism for 80 internal combustion engines, a starting circuit including a source of electrical energy, a starting motor and a starting switch for controlling said motor, means for actuating said starting switch including an electro-magnetic element and a control circuit therefor including the source of electrical energy and a control switch, electro-magnetic means 85 energized concomitantly with the starting circuit tending to open said control switch, electro-magnetic means energized simultaneously therewith for holding said control switch closed and thermostatic means energized from said starting circuit for rendering said holding means inoperative after a predetermined time interval.

7. In an automatic starting mechanism for 90 internal combustion engines, a starting circuit including a source of electrical energy, a starting motor and a starting switch for controlling said motor; means for actuating said starting switch including an electro-magnetic element and a control circuit therefor including the source of electrical energy and a control switch; a movable element for operating said control switch, a solenoid energized from said starting circuit tending to move said element in a direction to open said control switch, a solenoid traversed by the starting current for holding said element in position to close said control switch, and thermostatic means energized from said starting circuit for shorting the holding solenoid after the starting circuit has been closed a predetermined time.

8. In an automatic starting circuit including a source of energy, a starting motor and a starting switch for controlling said motor, opposed electro-magnetic elements adapted respectively to cause the switch to be held closed as long as the engine is being cranked and to be opened when the engine starts,

and means for rendering said holding element inoperative after the starting motor has been energized a predetermined length of time.

5 In testimony whereof I have signed this specification.
